UNITED STATES PATENT OFFICE.

WILLIAM SPALCKHAVER, OF NEW YORK, N. Y., ASSIGNOR TO ROBERT HOE,
OF SAME PLACE.

PRINTING-MACHINE.

SPECIFICATION forming part of Letters Patent No. 664,593, dated December 25, 1900.

Application filed June 2, 1900. Serial No. 18,794. (No model.)

To all whom it may concern:

Be it known that I, WILLIAM SPALCKHAVER, a citizen of the United States, residing at New York, county of Kings, and State of New York, have invented certain new and useful Improvements in Printing-Machines, fully described and represented in the following specification and the accompanying drawings, forming a part of the same.

10 This invention relates to rotary printing machines.

The invention has for its object to produce a rotary printing-machine which, considering its capacity, is arranged with compactness; 15 which shall embody sets of printing-couples and independent couples so arranged that the machine, while primarily intended to produce a product which shall consist both of perfected webs and webs printed in colors, 20 shall also be capable of a large variety of products; in which the runs of the webs are substantially directly through the machine; in which the printing members of the several couples are so arranged as to be readily 25 accessible either for the operations of making ready or the changing of plates, and in which the couples are so arranged that certain of them may be readily cut out either for the operations of making ready or to reduce 30 the capacity of the machine, this being done without interfering with the running of the couples which remain in operation.

As a full understanding of the improvements constituting the present invention can best be given by an illustration and a detailed description of an organization embodying the same, such a description will now be given in connection with the accompanying drawings, which illustrate one embodiment of the 35 invention, and in which—

Figure 1 is a side elevation of a printing machine embodying the invention, the several couples and sets of couples being arranged so that the machine is running as a sextuple with a full color-deck. Fig. 2 represents the same machine arranged as an octuple and at the same time printing one web in black on one side and in two colors on the other side. Fig. 3 represents the machine 45 running as a quadruple but printing each web in three colors on one side. Fig. 4 represents the machine running as a quadruple, the color-deck being cut out.

Referring to the drawings, 1 indicates the frame of the machine, in which are mounted 55 two sets of printing-couples B and C. The set of couples B embodies two form-cylinders 8 and 9 and two impression-cylinders 10 and 11, this set of couples being arranged to print and perfect a web. Similarly, the set of couples C embodies two form-cylinders 14 and 15 and two impression-cylinders 16 and 17, this set of couples being also arranged to print and perfect a web. The form-cylinders 8 and 9 of the set of couples B are provided 60 with inking apparatuses 12 and 13, which may be of any usual or desired description, and the form-cylinders 14 and 15 of the set of couples C are similarly provided with inking apparatuses 18 and 19. These sets of 65 couples are preferably arranged as shown—that is to say, the set B is spaced from the set C, so that the pressman may readily get between the couples for the purpose of making ready or for changing plates.

75 The machine as it is preferably constructed is provided with a full "color-deck," which term as understood in the art includes three couples which apply the three primary colors to the web and two couples which print in black. One of the couples which prints in black is arranged to deliver its impression on the same side of the web as the couples which print in colors, this black impression being made from a key-plate and being used to give 80 "expression" to the colored picture. The other couple which prints in black delivers its impression on the opposite side of the web. It is of course to be understood that a "color-deck" may include more couples than those 85 described; but as understood in the art the term includes at least the number of couples specified.

In the machine shown the color-deck consists of five couples, E, F, G, H, and I. Of 95 this set of couples the couple E is preferably arranged substantially centrally of the machine and above and between the sets of couples B and C. The couple E consists of a form-cylinder 20 and an impression-cylinder 100 21, the form-cylinder having any usual or desired form of inking apparatus 30, which is preferably arranged, as shown, at one side of the couple. The four couples F, G, H, and I, which constitute the remainder of the color-deck, are located in the frame above the 105

couples which constitute the sets B and C and above the couple E. One of these couples preferably embodies two impression-cylinders, the construction and arrangement being preferably that disclosed in the patent to me, No. 636,862, dated November 14, 1899. The couple F consists of a form-cylinder 22 and an impression-cylinder 23, the couple being provided with any usual or desired form 10 of inking apparatus 31. In the construction shown the couple G is the couple which embodies two impression-cylinders, these impression-cylinders being marked 25 50, the impression-cylinder 25 being used, as will be 15 hereinafter explained, when the web is running through the couple in one direction and the impression-cylinder 50 being employed when the web is running through the couple in the opposite direction. Coöperating with 20 these impression-cylinders 25 50 is a form-cylinder 24, the construction and arrangement of which is fully explained in the patent hereinbefore referred to. The other two couples H and I of the color-deck consist of 25 form-cylinders 26 and 28 and impression-cylinders 27 and 29, the couple I being the couple which when the color-deck is used delivers the final impression in black on the side of the web which is printed in colors. 30 The couples G, H, and I are provided with inking apparatuses 32, 33, and 34. The second and third couples of the color-deck are preferably arranged as shown—that is to say, they are spaced from the fourth and fifth 35 couples of the deck and the inking apparatuses are arranged over the couples.

The webs for the several couples are derived from any suitable source. In the construction shown the web for the set of couples 40 B is derived from the web-roll 35, that for the set of couples C from the web-roll 36, and that for the color-deck from the web-roll 38. Suitable guides are provided by which the webs are controlled as they pass to and between the several couples; but as these guides are or may be of any ordinary form of roll 45 guides or bars and as they will be arranged in the machine as the exigencies of the specific case require an extended description of them is not believed to be necessary.

The webs are all given a straight run through the machine and are all led to a common delivery mechanism, the webs being associated as they pass over a common roll 39, 55 from which they pass to a suitable delivery mechanism, (indicated at 40,) which may consist of a series of longitudinal folders. It is understood, of course, that a slitter or slitters (not shown) will be employed to coöperate with the roll 39, the slitters varying in 60 number according to the number of delivery mechanisms employed.

Each of the couples as the machine is preferably constructed will be arranged to print 65 on a double-wide web. It is to be understood, however, that the couples may, if desired, be arranged to print on a single-wide web. It

will be understood, however, that all the couples in the machine are arranged to print on a web of uniform width whether this web be 70 a single-wide or a double-wide web. The term "full width" as it is used in the specification and claims indicates that the web is uniform in width with the other webs printed in the machine.

The machine shown in Fig. 1, assuming the couples to be double wide, is arranged so that the couples in the set B print and perfect the web coming from the roll 35, and the set of couples in the set C print and perfect the web 80 coming from the roll 36. The web from the roll 38 is led first between the form-cylinder 20 and the impression-cylinder 21 of the couple E of the color-deck, by which couple it is printed in black on one side, this couple being, as before stated, arranged substantially centrally of the machine. From the couple E the web is led between the members of the couple F and then between the form-cylinder 24 and the impression-cylinder 25 of the couple G, after which it passes between the members of the couples H and I. The form-cylinders 22, 24, and 26 of the couples F, G, and H print three primary colors on the web, and the form-cylinder 28 delivers the final impression in black to the web. With this arrangement of the machine all the couples are employed, and the machine is running as a sextuple—that is, it produces with double-wide webs and suitable slitters two twelve-page 95 papers, each paper having an outer sheet or supplement printed in colors and having a final impression in black.

As shown in Fig. 2, the machine is arranged as an octuple. This octuple arrangement is 105 made possible without changing the direction of rotation of any of the couples by means of the additional impression-cylinder 50. In this construction the webs from the rolls 35, 36, and 38 are led as before, except that the web 38 after passing between the members of the couple F is by means of suitable guides carried directly to the delivery mechanism instead of being printed in colors. This web is therefore printed on one side in black and 110 is perfected in black on the opposite side, the fountain of the inking apparatus for the form-cylinder 22 being of course filled with black ink. In this arrangement of the machine an additional web-roll 51 is provided, and the web from this roll is led by suitable guides, 115 as shown in Fig. 2, between the form-cylinder 24 and the impression-cylinder 50 of the couple G. From this couple the web is led directly between the members of the couples H and I, from which it receives two impressions on the same side. After leaving the couple I the web is led to the delivery. The product of this arrangement of the machine, 120 assuming the usual deliveries, is two sixteen-page papers, the outer sheet of each paper having one page printed in colors, or, if desired, one of the form-cylinders 26 or 28 of the couples H or I may be provided with a half- 125 130

tone plate, in which case the half-tone picture will take the place of one of the colors.

In the construction shown in Fig. 3 the first couple E of the color-deck is cut out. In this arrangement only two webs are printed. The web from the roll 35 after being perfected by the couples in the set B is led through the couples H and I to the delivery. The web from the roll 36 after being perfected by the couples in the set C is led between the members of the couple F and between the form-cylinder 24 and the impression-cylinder 25 of the couple G. After leaving the couple G it is led by suitable guides around the couples H and I and meets and is associated with the other web at the delivery. In this arrangement the product of the press is two eight-page papers, the outer sheet of each paper having one page printed in three colors.

20 In the construction shown in Fig. 4 the entire color-deck is cut out, the machine running simply as a quadruple—that is to say, printing on two double-wide webs.

The gearing by which the cylinders are run 25 may be of any ordinary description. This gearing has no particular relation to the invention, and it is entirely within the power of any person skilled in the art of printing machinery to supply the same, and an illustration thereof has been omitted as unnecessary.

In all the arrangements of the machine it will be seen that the webs are given a direct run through the machine and that it is not necessary to reverse the direction of rotation 35 of any impression member of any couple. The machine is furthermore capable of a great variety of products and in addition to the arrangements described may be run 40 either as a sextuple printing in black or as an octuple printing in black. When run as a sextuple printing in black, the web would be led directly from the couple E to the couple I in an obvious manner, thus leaving 45 the three couples F, G, and H free, so that the operations of making ready may be performed on them. Furthermore, owing to the arrangement of couples in the frame all the form-cylinders can be readily reached, so that 50 a change of plates throughout the machine, or any part of it can be readily effected.

While the number of couples in the color-deck will preferably be that shown, it will be understood of course that more couples 55 may be used in it, if desired. Furthermore, while a full color-deck will preferably be used the invention in all its features is not limited to the use of such a deck.

What is claimed is—

60 1. In a printing-machine, the combination with a suitable frame, of a single printing-couple mounted substantially centrally of the frame, two sets of printing-couples, one set being mounted below and at one side of the centrally-mounted couple and the other set being mounted below and at the other side of 65 said centrally-mounted couple, and a series

of couples mounted in the frame and arranged over the couple and sets of couples, substantially as described.

70

2. In a printing-machine, the combination with a suitable frame, of a single printing-couple mounted substantially centrally of the frame, two sets of printing-couples, one set being mounted below and at one side of the centrally-mounted couple and the other set being mounted below and at the other side of 75 said centrally-mounted couple, a series of couples mounted in the frame and arranged over the couple and the sets of couples, and a common delivery mechanism to which all the webs are led, substantially as described.

80

3. In a printing-machine, the combination with a suitable frame, of a single printing-couple capacitated to print a full-width web 85 and mounted substantially centrally of the frame, two sets of printing-couples, one set being mounted below and at one side of the centrally-mounted couple and the other set being mounted below and at the other side of 90 said centrally-mounted couple, each set of couples being capacitated to print and perfect a full-width web, and a series of couples capacitated to print and perfect a full-width web mounted in the frame and arranged over 95 the couple and the sets of couples, substantially as described.

90

4. In a printing-machine, the combination with a suitable frame, of a single printing-couple capacitated to print a full-width web 100 and mounted substantially centrally of the frame, two sets of printing-couples, one set being mounted below at one side of the centrally-mounted couple and the other set being mounted below and at the other side of 105 said centrally-mounted couple, each set of couples being capacitated to print and perfect a full-width web, a series of couples capacitated to print and perfect a full-width web mounted in the frame and arranged over the couple 110 and the sets of couples, and a common delivery mechanism to which all the webs are led, substantially as described.

105

5. In a printing-machine, the combination with a frame, of two sets of couples mounted 115 therein, each set of couples being capacitated to print and perfect a web, and a color-deck, one couple of which is arranged above and between the two sets of couples and the remainder of which are arranged over the sets 120 of couples, substantially as described.

115

6. In a printing-machine, the combination with a frame, of two sets of couples mounted therein, each set of couples being capacitated to print and perfect a web, a color-deck, one 125 couple of which is arranged above and between the two sets of couples and the remainder of which are arranged over the sets of couples, and a common delivery mechanism to which all the webs are led, substantially as described.

125

7. In a printing-machine, the combination with a frame, of two sets of couples mounted therein, each set of couples being capacitated

130

to print and perfect a full-width web, and a color-deck, capacitated to print a full-width web, one couple of which is arranged above and between the two sets of couples and the remainder of which are arranged over the sets of couples, substantially as described.

8. In a printing-machine, the combination with a frame, of two sets of couples mounted therein, each set of couples being capacitated to print and perfect a full-width web, a color-deck capacitated to print a full-width web, one couple of which is arranged above and between the two sets of couples and the remainder of which are arranged over the sets of couples, and a common delivery mechanism to which all the webs are led, substantially as described.

9. In a printing-machine, the combination with a suitable frame, of a plurality of sets of couples mounted therein, each set being arranged to print and perfect a full-width web, and a plurality of couples mounted in the frame independently of and over the sets of couples, one of said couples consisting of a form-cylinder and two impression-cylinders, either of which may be caused to co-operate with the form-cylinder, said independently-mounted couples being arranged so that they may be used to print a full-width web in black and perfect it in colors, or a part of them may be used to print and perfect a full-width web in black, substantially as described.

10. In a printing-machine, the combination with a suitable frame, of a plurality of sets of couples mounted therein, each set being arranged to print and perfect a full-width web, a plurality of couples mounted in the frame independently of and over the sets of couples, one of said couples consisting of a form-cylinder and two impression-cylinders, either of which may be caused to co-operate with the form-cylinder, said independently-mounted couples being arranged so that they may be used to print a full-width web in black and perfect it in colors, or a part of them may be used to print and perfect a full-width web in black, and a common delivery mechanism to which all the webs are led, substantially as described.

11. In a printing-machine, the combination with a suitable frame, of a plurality of sets of couples mounted therein, each set being capacitated to print and perfect a full-width web, and a color-deck located over the sets of couples, the first and last couples of which are arranged to print on opposite sides of a full-width web and the intermediate couples being arranged to print on one side of the web, one of said intermediate couples consisting of a form-cylinder and two impression-cylinders, either of which may be caused to co-operate with the form-cylinder, substantially as described.

65 12. In a printing-machine, the combination

with a suitable frame, of a plurality of sets of couples mounted therein, each set being capacitated to print and perfect a full-width web, a color-deck located over the sets of couples, the first and last couples of which are arranged to print on opposite sides of a full-width web and the intermediate couples being arranged to print on one side of the web, one of said intermediate couples consisting of a form-cylinder and two impression-cylinders, either of which may be caused to co-operate with the form-cylinder, and a common delivery mechanism to which all the webs are led, substantially as described.

13. In a printing-machine, the combination with a suitable frame, of two sets of printing-couples mounted therein, each set being capacitated to print and perfect a full-width web, a printing-couple capacitated to print a full-width web arranged above and between said sets of couples, and a plurality of printing-couples capacitated to print a full-width web mounted over the sets of couples, one of said couples consisting of a form-cylinder and two impression-cylinders, either of which may be caused to co-operate with the form-cylinder, substantially as described.

14. In a printing-machine, the combination with a suitable frame, of two sets of printing-couples mounted therein, each set being capacitated to print and perfect a full-width web, a single printing-couple capacitated to print a full-width web arranged above and between said sets of couples, a plurality of printing-couples capacitated to print a full-width web mounted above the sets of couples, one of said couples consisting of a form-cylinder and two impression-cylinders, either of which may be caused to co-operate with the form-cylinder, and a common delivery mechanism to which all the webs are led, substantially as described.

15. In a printing-machine, the combination with a suitable frame, of two sets of printing-couples mounted therein, each set being capacitated to print and perfect a full-width web, a printing mechanism capacitated to print a full-width web arranged above and between said sets of couples, a plurality of printing-couples capacitated to print a full-width web mounted above the sets of couples, one of said couples consisting of a form-cylinder and two impression-cylinders, either of which may be caused to co-operate with the form-cylinder, and a common delivery mechanism to which all the webs are led, substantially as described.

In testimony whereof I have hereunto set my hand in the presence of two subscribing witnesses.

WILLIAM SPALCKHAVER.
